[57] CLAIM

The ornamental design for a pan head mounting assembly for tripod, substantially as shown and described.

DESCRIPTION

FIG. 1 is a front perspective view of a pan head mounting assembly for tripod showing my new design, the broken line showings of the tripod legs are environmental only and form no part of the claimed design;

FIG. 2 is a rear perspective view thereof;

FIG. 3 is a top plan view thereof;

FIG. 4 is a bottom plan view thereof;

FIG. 5 is a front perspective view of another embodiment of my new design of FIGS. 1-4, the broken line showings of the tripod legs and connector legs are environmental only and form no part of the claimed design;

FIG. 6 is a rear perspective view of FIG. 5;

FIG. 7 is a bottom plan view of FIG. 5.
